UNITED STATES PATENT OFFICE.

JOHAN OSCAR LIFFLANDER, OF STOCKHOLM, SWEDEN, ASSIGNOR TO J. & C. G. BOLIN-
DERS MEK. VERKSTADS AKTIEBOLAG, OF STOCKHOLM, SWEDEN, A CORPORATION.

PLANING CUTTER.

Application filed January 27, 1925, Serial No. 5,121, and in Sweden February 7, 1924.

Heretofore, planing cutters of a great width, that is to say of great extension in the axial direction, and provided with continuous cutting edges, have suffered from a 5 number of great disadvantages. In the manufacture of such cutters great difficulties are met with in tempering and grinding the wide cutting edges, or in otherwise preparing the same, without flaws setting in 10 in the material, and a matter of still greater importance is, that if the cutting edge is injured in any place during work, for instance, by hitting a nail, generally the whole cutting edge will become unfit for work, 15 which, naturally is a circumstance of great importance from the point of view of cost.

For this reason the cutting edge has been divided into sections along the width thereof, that is to say, along the axis of the cutter. If in such a section the cutting edge is 20 injured, the section having the injured edge may be easily replaced by a new one, and thus the whole planing cutter need not be discarded.

25 In a cutter divided in the manner set forth, however, the rigid connection between the sections will be a matter of the utmost importance, a safeguard having to be provided against any one of the sections separating from the others, in case it happens 30 to burst during work or is otherwise injured. The object of the present invention is to provide such mutual connection between the sections that they may, practically, be regarded as a continuous whole piece, while 35 excluding every possibility of any one of the sections separating from the others, if the sections are not deliberately taken apart.

This is secured, according to the invention, by the arrangement of locking means 40 between the sections, which locking means embrace or grip the sections in such a manner that the parts of a section that may have burst cannot separate under the action of the centrifugal force. The locking parts 45 should preferably be made of a tougher material than the sections proper. Between the latter, therefore, special locking rings of such tougher material are preferably provided, the said locking rings having such a 50 cross section that the rings, co-operating with the correspondingly shaped end profiles of the sections, are caused to lock the sections onto each other by pressure in a 55 radial direction, when the said locking rings

and the sections are pressed together axially.

In the accompanying drawing, an embodiment of the invention is illustrated by way of example. Fig. 1 is an elevation of the cutter, the one half thereof being shown 60 in longitudinal section. Fig. 2 shows one of the cutter sections viewed in the axial direction, and Fig. 3 shows the same section viewed from the side and in the axial direction.

In the embodiment illustrated, the planing cutter is divided into three annular sections 1 each section comprising a hub portion and a plurality of blade portions, the blade portions being of greater width than the remainder of the section and being adapted to be aligned with each other when the cutter is assembled to form substantially continuous blades, as shown in Fig. 1. The sections 1 are slid onto the cutter spindle 2, and between each pair of sections there is slid onto the spindle a locking ring 3 which, in the case illustrated, is of a nearly trapezoidal, inwardly tapering cross section. The 70 end portions of the cutting sections 1 are 80 shaped correspondingly, in a conical fashion, and will thus be embraced or gripped by the rings 3, which securely prevent separation of the parts of a section that may have burst. Outside the outer ends of the two 85 extreme sections there are also provided similar rings 4, one of which bears against a boss 5 on the spindle 2, while the other bears against the nut 6 which is screwed onto the threaded end portion of the spindle 90 2 and serves to force the whole structure together. To secure rigid engagement between the sections 1 and the locking rings 3 and 4, the contact surfaces of the parts 95 may be grooved, as shown in the drawing.

As already set forth hereinbefore, the surfaces of the locking means co-operating with each other may be of any suitable outline effecting the locking aimed at. For instance, the said outline may be step-like or wavy. However, the outline shown in the drawing is preferred from a practical point of view, and the conical shape may, as shown to the extreme left of the drawing, be altered into a slight spherical shape.

100 What I claim as new and desire to secure by Letters Patent of the United States of America is:—

105 A rotary planing cutter comprising a plurality of annular sections mounted on a 110

shaft, the adjacent surfaces of said sections being recessed to form inwardly tapering annular spaces of approximately trapezoidal cross section between the sections, annular locking members fitting in said spaces and having surfaces engaging said adjacent surfaces of the sections, the surfaces of said locking members being roughened to enable the locking members to securely grip said adjacent surfaces, each of said sections be-

ing provided with longitudinally extending blade portions of greater width than the remainder of the section, the blade portions of the several sections being adapted to be aligned with each other when the cutter is 15 assembled, to form substantially continuous cutting blades, and means exerting axial pressure on said sections.

In testimony whereof I affix my signature.
JOHAN OSCAR LIFFLANDER.
